DETACHABLE CARD HOLDER
FOR PURSES

Eldon C. Henderson, Paso Robles, Calif.

Application April 29, 1950, Serial No. 159,120

3 Claims. (Cl. 150—39)

1

This invention relates to detachable card holders for purses which are also useful for preventing loss of purses from pockets of articles of clothing, such as trouser pockets, and is particularly concerned with a simple, practical and inexpensive device which may be removably engaged to a purse. As used in the present specification and claims, the term "purse" includes billfolds, pocketbooks, wallets and the like.

Various mechanical safety attachments for billfolds, pocketbooks and the like have been proposed heretofore but have for various reasons not gained wide acceptances because they in most instances include metal frames or pivoted, rigid arms affixed to the billfold for engaging the pocket after insertion into it, which are difficult to operate or are so bulky as to deform the clothing and/or wear out parts of the pocket in contact therewith.

There is need for a card holder for billfolds which can be readily detached from the billfold to permit the owner to display or deliver an identification card, credit card, or the like, without surrendering his complete billfold. Applicant found that such a card holder should have a cooperative function with respect to the billfold so as to be habitually placed together with the billfold, and yet be readily extractable from and assembled to the billfold. Various detachable holders heretofore proposed have been secured to the billfold by a snap fastener which, in practice, requires care and time when the holder is again secured to the billfold; on the other hand, holders which are inserted loosely into a pocket or compartment in the billfold have the drawback that the holder must be identified and segregated from other cards usually placed in such pocket or compartment. Simply placing such a holder loosely in the billfold often results in accidental loss or misplacement of the card holder.

It is, therefore, an object of this invention to provide an improved card holder which is completely separate from and is readily detachable from or inserted into a purse and is adapted to hold one or more cards, the holder being of simple construction and causing no personal discomfort to the person on whose person it is used when within the pocket of an article of clothing.

It is a further object to provide an improved card holder having a main purse-engaging portion adapted to retain one or more cards and a hinged guard tab which may be folded over the purse to permit insertion into or extraction from the pocket and which, when unfolded to lie in prolongation of the main purse-engaging portion

5 is adapted to engage the cloth forming the pocket to prevent accidental movement or unauthorized extraction of the purse through the mouth of the pocket, the tab serving also as a handy means for withdrawing the device from the purse.

Other objects are to provide a card holder performing the added function of securing a purse against loss from a pocket, which holder adds 10 but little bulk to the purse; wherein the added guard tab may be utilized for indicia, such as identification and/or advertising; and which can be manufactured at a very low cost and is suitable for free distribution as advertising.

15 Briefly, according to the present invention the card holder is provided with a main, purse-engaging and card-holding tab adapted to be inserted into the purse from the side, and a guard tab secured to the main tab by a hinge along a 20 hinge line which is perpendicular to the pocket opening when the purse is in its normal position within the pocket. The main tab has a width (measured in a direction parallel to the pocket opening) which does not substantially exceed 25 the width of a normal purse and is, preferably, equal to or somewhat shorter than said width of the purse, and the width of the guard tab is such that the combined widths of the main and the guarded tabs, exceeds the said width of the 30 purse and, preferably, exceeds the width of the pocket opening. Both the main and the guard tab are made of thin, stiff sheet material which may have some flexibility, and the main part is formed of two or more laminations preferably 35 transparent, open at one or more margins to permit a card to be inserted between the laminations. These laminations or at least one of them may be made of any transparent sheet material such as transparent plastic material and the 40 guard tab may be made of the same material or of a more rigid sheet material which is better able to resist wear due to contact with the pocket.

The hinge is preferably constructed of one or 45 more sheets of fabric or other very flexible material such as oilcloth, flexible plastic sheet material, imitation leather ("Leatherette"), etc., arranged to maintain the juxtaposed edges of the main part and guard tab in spaced relation so that the guard tab can be folded over the outside of the purse and made to lie in a plane offset by about half of the thickness of the purse from the plane of the main part of the device. The width of this interval between the two tabs may be selected as desired, taking into account 50 the size of purse, and it has been found that in

ervals of between about one sixteenth and one quarter of an inch are suitable for most purposes. This interval is, of course, an optional feature, and may be omitted when a sufficiently flexible guard tab is used.

The hinge is preferably constructed of two sheets of fabric or other very flexible material so as to have a tendency to cause the guard tab to unfold into the plane of the main tab. This facilitates movement of the guard tab into operative position after insertion of the assembled purse and loss preventing device into the pocket without need to grasp the guard tab at its edge when folded alongside of the purse and then fold it outwards with the end of the finger. With this preferred construction the guard tab, when released, tends to unfold, but is usually prevented from moving to its fully operative position by engagement thereof with the pocket lining; it is merely necessary to distend the lining momentarily, to free the guard tab for completing its movement to operative position.

The width of the guard tab is, in the preferred form, somewhat less than the width of the main tab, thereby facilitating the movement of the guard tab about its hinge while within the pocket.

The invention will be better understood by reference to the accompanying drawing forming a part of this specification and showing a preferred embodiment of the invention by way of illustration. In the drawing:

Fig. 1 is an elevation view of a card holder in unfolded or operative position;

Fig. 2 is an enlarged sectional view taken on line 2—2 of Fig. 1;

Fig. 3 is an elevation view, on a reduced scale, of a purse to which the card holder has been applied and which is secured within a pocket, the pocket lining being shown in section;

Fig. 4 is a horizontal section view taken on line 4—4 of Fig. 3; and

Fig. 5 is a horizontal sectional view corresponding to Fig. 4 but showing the guard tab in its inoperative position, folded back against the outside of the purse for permitting passage through the pocket opening.

Referring to the drawings, the card holder comprises a main purse-engaging and card-holding tab 10 and a guard tab 11 connected thereto by a hinge 12. The materials are of thin sheet material and all thicknesses have been greatly exaggerated in Figs. 2, 4 and 5. The main tab 10 consists of a single piece of transparent plastic material folded at the outer edge 13 to provide a pair of transparent covers and leaving the upper and lower edges 14 and 15 free for the insertion of identification or other cards, such as the card 16. Both covers terminate at the inner edge 17 of the main tab; this edge is spaced slightly from the inner edge 18 of the guard tab. The hinge 12 connecting these tabs is made of two strips of fabric tape or the like, shown at 19 and 20, secured to opposite sides of the tabs as shown in Fig. 2 by any suitable means, for example by an adhesive and/or stitching. The two transparent covers are held together at the edge 17 by either of two means, both of which may be used in combination: (a) The juxtaposed parts of the tapes 19 and 20 in the interval between the edges 17 and 18 are joined by adhesive or stitching. (b) The tapes are stitched together by stitching through the transparent sheets as shown at 21 in Fig. 1. It was found in actual use that adhesive alone permits the tape to slide or "creep" gradually over the smooth surfaces

of the sheet material used for transparent covers and the guard tab when the device is put to extended use and that stitching is desirable to prevent such relative motion; for this purpose the tapes are also stitched to the guard tab as shown at 22. While stitching may constitute the sole means of securing the tapes to the tabs it is preferred to use adhesive in addition to prevent the loose edges of the tape from becoming frayed with use. The two parallel sheets of tape have a tendency to urge the guard tab to its unfolded, operative position regardless of the direction toward which it is folded.

The width of the card holder, from the outer edge 13 to the outer edge 23 is slightly greater than the width of the mouth or opening of the pocket of the clothing within which the purse is to be secured, e. g., a hip trouser pocket. The width of the purse-engaging main tab 10 is approximately equal to or slightly less than the width of the purse, while the width of the guard tab 11 is somewhat less than that of the main tab. Moreover, it is preferred to cut away the outer margin of the guard tab as shown at 24 to decrease the width toward the bottom and, further, to cut off the lower, outer corner 25, making the lower edge shorter than the upper edge to fit into the pocket without binding.

When in place to secure a purse in the rear hip pocket the device is usually positioned with the guard tab toward the center of the body and the hinge is vertical, as shown in Fig. 3, with the wider edge of the device toward the top. The upper edge thereby can engage the inner side of the pocket lining for preventing accidental or unauthorized extraction of the purse with which the device is engaged.

In using the device the main, card-holding and purse-engaging tab 10 is inserted into a purse of any suitable type having a side opening, e. g., by inserting that part into any compartment which opens to one side, or into loops especially provided for the purpose, etc. In the example illustrated in Figs. 3-5, the purse is shown as a billfold 26 of the type that is folded along a transverse axis. The card holding device is attached by placing the main tab between the opposed sections with the shorter edge toward the folded edge 27 of the purse. To insert the billfold into the rear left hip trouser pocket shown, the guard tab is folded over the outer face of the billfold, as illustrated in Fig. 5, such folding being possible because of the interval between the edges 17 and 18. The assembled purse and card holding device are then grasped in folded position and lowered through the opening 28 of the pocket with the hinge 12 vertical and the folded edge 27 down. The guard tab is then released and the lining 29 of the pocket is moved away from the purse for a small distance, permitting the guard tab to rotate outwardly to assume its operative position shown in Fig. 3. With some hinge materials it is necessary to rotate the hinge into operative position by using the fingers. The billfold usually assumes a position at the center of the pocket with the edge 13 projecting to the left of the purse, although this will not always occur with purses which are not open at both side edges. In the billfold shown, wherein the side edges 30 and 31 of the billfold are both open, the outer edges 13 and 23—24 of the tabs are free to engage the lining 29; but since the total width of the device is slightly less than the width of the usual hip trouser pocket these edges do not exert a distending force against the lining. It is evident that the

card holding device will not pass through the pocket opening in the position illustrated in Fig. 3, and that engagement of the inner side of the folded edge 27 of the billfold with the device prevents the billfold from being removed.

To remove the purse from the pocket the tab 11 is folded over the outer face of the purse and the purse and card holding device are raised simultaneously. To display the card 18 contained in the holder it is a simple matter to pull on the tab 11 and separate the device from the billfold. This is a great convenience in many situations, for example, at automotive service stations where it is customary to hand a credit card to an attendant and it is desired not to hand him the entire billfold. Since the device is normally used to lock the purse in the pocket and thus functionally associated therewith it is unlikely that the device and purse will be thoughtlessly separated, so that the former objection to an independent card holder is obviated.

This application is a continuation-in-part of my copending application Serial No. 59,549, filed November 12, 1948, now Patent No. 2,580,296.

I claim as my invention:

1. A detachable card holder adapted to be attached to a purse and to extend beyond the margin of the purse when the purse and holder are within a pocket of an article of clothing comprising a main purse-engaging tab comprising a single piece of transparent sheet material folded on itself to form a pair of transparent covers providing therebetween a card-holding space open at a margin thereof to permit a card to be inserted; a guard tab comprising a sheet of thin, relatively stiffer material; and a hinge of very thin, highly flexible material secured to the faces of said tabs and joining said guard tab to the main tab, the aggregate width of card holder in a direction perpendicular to the hinge between the remote edges being only slightly greater than the width of the opening of said pocket to permit the tabs to be unfolded within the pocket with the hinge substantially perpendicular to said openings and both tabs having widths less than the width of said opening, whereby the purse-engaging tab may be engaged with a purse and

the guard tab may be folded on said hinge to permit passage of the purse and card holder through said opening.

2. A detachable card holder adapted to be removably attached to a purse and to extend beyond the margin of the purse when the purse and card holder are within a pocket of an article of clothing comprising a main purse-engaging tab and a guard tab connected by a hinge, both of said tabs being made of thin, stiff sheet material, said purse-engaging tab comprising a plurality of laminations at least one outer one of which is transparent and providing therebetween a card-holding space open at a margin thereof to permit a card to be inserted, and the guard tab being of sheet material heavier and stiffer than said transparent material to resist wear, the aggregate width of the device in a direction perpendicular to the hinge between the remote edges being slightly greater than the width of a purse and the width of each of said tabs in the said direction being not substantially in excess of said width of the purse.

3. The card-holder according to claim 2 wherein the purse-engaging tab has a width, measured in the said direction, substantially equal to the width of the purse and the guard tab has a width that is materially less than the width of the purse.
